CLAIM

The ornamental design for a decompression toy, as shown and described.

DESCRIPTION

FIG. 1 is a front perspective view of a decompression toy, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view 1 showing the decompression toy in a use state; and,

FIG. 10 is a perspective view 2 showing the decompression toy in a use state.

The broken lines in the drawings illustrate the portions of the decompression toy, which form no part of the claimed design.

1 Claim, 10 Drawing Sheets
